APPLIANCE FOR USE IN FORMING SEPARATE COMPARTMENTS IN CARDBOARD UNITS

Leslie Rex Whiby, London, England, assignor to R. H. Filmer Limited, London, England, a British company

Application September 16, 1950, Serial No. 185,294

4. Claims. (Cl. 93—37)

This invention relates to insets for boxes for the purpose of conveniently packing in spaced relation various articles or fruit such as apples, eggs and tomatoes.

The insets are generally constructed from a sheet of cardboard or like material which is suitably scored and slit and formed into a tubular element of rectangular cross-section. One or more of these insets may be placed side by side in the box.

Insets of this character are described, for example, in the specification of U. S. A. patent application Serial No. 45,079, now U. S. Patent 2,690,866, issued Oct. 5, 1954, for example with reference to Fig. 21.

It has now been found that it is slow and difficult to form these cartons into shape from the tube by bending the material along the scored portions of the inset for forming the separate compartments.

It is the object of the present invention to provide an appliance which overcomes this difficulty of bending the inset along the scored lines.

An appliance for use in forming compartments in one inset is provided with a base on which are provided a number of upstanding projections each of a length and width so as to engage with the area defined by a scoring line and its associated slits in the bottom of the inset.

The appliance may be provided at opposite ends with stops which serve to position the inset relatively to the upstanding projections so that these pass into the bottom of the inset when the latter is pressed downwardly on the projections.

The appliance may be provided with a plunger device having a number of plungers corresponding with the shape and number of compartments to be formed in the inset.

The plunger device may be hinged to the base on which the upstanding projections are provided and may be acted upon by one or more springs serving to move it into its inoperative position.

The ends of the plungers are preferably shaped to facilitate their engagement with the inset for forming the separate compartments.

The invention will now be described by way of example with reference to the accompanying drawings, wherein:

Fig. 1 shows an underside of a tubular member.

Fig. 2 shows the tubular member in Fig. 1 after flaps therein have been pressed inwardly.

Fig. 3 shows a top view of the container suitably scored for forming pockets.

Fig. 4 shows a top view of the container after pockets have been formed therein.

Fig. 5 is an end view of Fig. 1.

Fig. 6 is a view of Fig. 4 looking in the direction of the arrow A.

Fig. 7 is a side view of an appliance for forming the pockets in the container as shown in Figs. 4 and 6.

Fig. 8 is a view looking in the direction of the arrow B in Fig. 7.

Fig. 9 is a plan view of Fig. 8.

Fig. 10 is a partial view looking in the direction of the arrow C in Fig. 7.

2

Fig. 11 is a perspective view of a plunger.

Referring first to Figs. 1 to 6, a blank of cardboard or like material is scored in the manner as described with reference to Fig. 21 in the specification of application No. 45,079.

At the portions of the blank at which two compartments are adjacent one another, a single scoring line may be provided, or, as shown, two spaced scoring lines 1, 2 are provided so that the walls 3, 4 of the adjacent cells 5, 6 may pass partly under the portion 7 of the inset between the two cells 5, 6 and thus bear resiliently against articles when placed into the cells 5, 6.

In the portion 9 of the blank which is to form the bottom of the inset there are provided, in such position as to be opposite the single scoring lines or opposite each pair of spaced scoring lines 1, 2 when the blank has been formed into a tubular member of rectangular cross-section, a spaced scoring line 10 and a slit 11. The ends of each slit 11 are connected to the ends of the adjacent scoring line 10 by slits 12, 13 extending at right angles to the slits 11 and scoring lines 10, whereby flaps are formed at 14. Instead of the slits 11, 12, 13 and scoring lines 10, slots may be provided.

Near each end of the portion of the blank for forming the bottom of the inset is provided a scoring line 14, 15 parallel to the previously mentioned slits 11 and scoring lines 10 and extending completely across the bottom portion, the scoring lines 14, 15 near the ends being connected at their opposite ends to the end of the blank by slits 16, 17, 18, 19 which extend to the ends of the blank so as to form flaps at opposite ends of the bottom.

In order to form compartments in the tubular member the appliance shown in Figs. 7 to 11 is provided with a base 20 to which are secured a number of upstanding projections 21, 22, 23. The projections 21, 22, 23 are of a width, breadth and height so that when the tubular member is placed on the upstanding projections 21, 22, 23 with the latter in register with the flaps 14, and the tubular member is pressed downwardly, the upstanding projections 21, 22, 23 enter the tubular member until they meet the inside of the top of the tubular member.

When hard articles are to be placed into the inset, one into each compartment, the placing of these articles and applying pressure thereto serves to bend the top of the inset along the scoring lines 10 so as to form the separate compartments, such as 5, 6, for receiving the separate articles, without crushing down the partition between the compartments.

In order to position the tubular member relatively to the upstanding projections 21, 22, 23 suitable stops 25, 26 are provided at opposite ends of the row of upstanding projections 21, 22, 23 and further stops such as 27, 28 are provided at or near the ends on one side of the upstanding projections. A central stop 29 is also provided in alignment with the stops 27, 28.

When the tubular member has been fitted on the upstanding projections 21, 22, 23 and the stops 25, 26, the cells may be formed manually by pressing the top of the inset inwardly along the scoring lines 10, without the risk of crushing down the partition between the cells 5, 6.

If desired the side walls of the upstanding projections 21, 22, 23 may be recessed on their opposite faces, whilst the inner faces of the walls of the stops 25, 26 may be similarly recessed.

The cells such as 5, 6, however, are preferably formed by means of a plunger device having plungers 30 of which the number preferably corresponds with the number of cells to be formed. The plungers 30 have the general shape of the cells to be formed. Each plunger has a reduced end 31 so as to facilitate its entrance into the slit 41, the reduced end 31 gradually merging, as

shown in Fig. 11, into the shape corresponding with the shape of the cells 5, 6.

The plungers 30 are mounted on a support 32 which is hinged at 33 to members 34 mounted on the base 20. The support 32 is preferably spring actuated, as indicated at 35, the spring action normally tending to move the plungers away from the cells.

The action of the springs 35 is limited by chains 36.

I claim:

1. An appliance for use in forming compartments in a cardboard unit of tubular outline wherein such unit is provided with pairs of spaced score lines extending transversely thereof at spaced intervals to form compartments intermediate such score lines in the top wall of the unit, a score line and a slit in the bottom wall opposite each pair of score lines in the top wall, a slit at each end of each of said last named score lines arranged at right angles thereto and extending to the slit to form a flap at both sides of the compartments intermediate the pairs of score lines and a score line at each of the outermost compartments along the bottom and a slit at each end of said last named score lines arranged at right angles thereto and merging therewith to form a flap at the outer side of each of the outermost compartments comprising a base, a plurality of spaced upstanding projections on said base, the projections being of such a thickness to permit the projections to enter the flap openings and being of sufficient height and width to engage and support the top wall of the tubular unit substantially completely thereacross a support hingedly connected to said base for movement toward and away from said projections, a plurality of spaced plungers secured to said support and depending therefrom adapted to co-operate with the space between adjacent pairs of said upstanding projections, each of said plungers having a reduced elongated end, and a spring located between said base and said support normally holding said support away from said projections.

2. An appliance for use in forming compartments in a unit of tubular outline wherein such unit is provided with pairs of spaced score lines extending transversely thereof at spaced intervals to form compartments intermediate such score lines in the top wall of the unit, a score line and a slit in the bottom wall opposite each pair of score lines in the top wall, a slit at each end of each of said last named score lines arranged at right angles thereto and extending to the slit to form a flap at both sides of the compartments intermediate the pairs of score lines and a score line at each of the outermost compartments along the bottom and a slit at each end of said last named score lines arranged at right angles thereto and merging therewith to form a flap at the outer side of each of the outermost compartments comprising a base, a number of spaced upstanding projections on said base, the projections being of such a thickness as to permit the projections to enter the flap openings and being of sufficient height and width to engage and support the top wall of the tubular unit substantially completely thereacross, stops

on said base at opposite ends of said row of upstanding projections for positioning said tubular unit relatively to said projections, further stops on one side of said projections, a plunger device hinged to said base for movement toward and away from said projections, said plunger device including a plurality of spaced plungers, for co-operation with said projections in order to form cells in said tubular member, each of said plungers having a reduced end which merges gradually into the main portion of the plunger which corresponds with the shape of a cell to be formed.

3. An appliance according to claim 1, wherein each plunger is of general rectangular shape having an end projecting portion extending across the end face of the plunger and having inclined faces which connect the projecting portion to the rectangular portion of the plunger.

4. An appliance for use in forming compartments in a cardboard unit of tubular outline wherein such unit is provided with pairs of spaced score lines extending transversely thereof at spaced intervals to form compartments intermediate such score lines in the top wall of the unit, a score line and a slit in the bottom wall opposite each pair of score lines in the top wall, a slit at each end of each of said last named score lines arranged at right angles thereto and extending to the slit to form a flap at both sides of the compartments intermediate the pairs of score lines and a score line at one end of the outermost compartments along the bottom and a slit at each end of the last named score lines arranged at right angles thereto and merging therewith to form a flap at the outer side of each of the outermost compartments, comprising a base, a plurality of spaced upstanding projections, the projections being of such a thickness to permit the projections to enter the flap openings and being of sufficient height and width to engage and support the top wall of the tubular unit substantially completely thereacross, stops on said base at opposite ends of the row of said upstanding projections, further stops at the ends on one side of said upstanding projections, a central stop in alignment with said last mentioned stops, a spring-actuated support hinged to said base for movement toward and away from said projections, a plurality of spaced plungers secured to said support, each of said plungers having a reduced end extending centrally across the same and then merging gradually into a shape corresponding with cells to be formed, and chains connected to the support and base limiting the spring action on the support.
